UNITED STATES PATENT OFFICE.

REINHARD WENDT, OF MUSKEGON, MICHIGAN.

COMBINED SHADE, CURTAIN, AND DRAPERY SUPPORT FOR ROLLERS.

973,829.

Specification of Letters Patent. Patented Oct. 25, 1910.

Application filed February 28, 1910. Serial No. 546,351.

To all whom it may concern:

Be it known that I, REINHARD WENDT, a citizen of the United States, residing at Muskegon, county of Muskegon, and State 5 of Michigan, have invented a certain new and useful Combined Shade, Curtain, and Drapery Support for Rollers, of which the following is a specification.

My invention relates to combined shade, 10 curtain and drapery supports for window frames and has for its object the production of a device of the character stated which shall be of simple construction and efficient in its operation.

15 The invention consists in the combination and arrangement of parts hereinafter described and claimed.

The invention will be more readily understood by reference to the accompanying 20 drawings forming a part of this specification, and in which,

Figure 1 is a perspective view of the upper portion of a window and frame equipped with supports embodying my invention, Fig. 25 2 is a sectional plan view of the same, Fig. 3 is an enlarged sectional elevation of one of the supports, Fig. 4 is an enlarged sectional elevation of the other support, Fig. 5 is a perspective view of one of the socket plates 30 employed in the construction, and Fig. 6 is a perspective view of a modified form of wire supporting member.

The preferred form of construction as 35 illustrated in Figs. 1 to 5 of the drawings comprises socket plates 1 having outwardly bent or offset socket portions 2 adapted in conjunction with the face of the window frame when said plates are secured in position to form narrow receiving sockets. 40 Each of the plates is provided with a screw hole 3 through which a screw 4 may be passed onto the window frame to secure the plate in position to form the receiving socket 5. The supporting members are 45 formed of horizontally disposed wire support members 6 and 7 connected by means of a vertically disposed loop or bend 8. The bend 8 is preferably flattened for ready insertion into socket 5 and members 6 and 7 50 are horizontally inclined thereto for a purpose to be hereinafter mentioned. Members 6 and 7 are of different lengths and are provided with upwardly turned outer ends 9 and 10 adapted to receive rods for supporting 55 curtains or other draperies.

One of the socket plates carries an angu-

lar shade support 11 having a rectangular aperture 12 adapted to receive one end of a shade roller. The inner portion of member 11 is provided with a slot 13 adapted to engage a bolt 14 projecting from the lower portion of socket 5 and equipped with a wing nut 15 by means of which plate 11 may be adjustably secured to plate 1. The other plate 1 is provided with a stud bolt 16 secured in position by means of a nut 17 lying within socket 5. Stud 16 carries an angular shade supporting member 18 the inner cylindrical portion of which slides through an aperture in stud 16. A spring 19 imprisoned between a collar 20 and stud 16 serves to yieldingly hold support 18 in its innermost position. A set screw 21 in stud 16 contacts with a flattened side of support 18 and serves to lock said support 75 in any desired adjusted position. By this arrangement it will be observed that a shade roller 22 may be readily inserted or removed in or from supports 11 and 18 and that supports 6 and 7 may be utilized to support curtain or other drapery rods 23 and 24 at different distances from the window frame, as indicated in dotted lines in Fig. 2. By inclining the members 6 and 7 to the bend 8 their outer end will be projected outwardly 80 as indicated in Fig. 2 for the purpose of better accommodating rods which are as long or longer than the shade employed.

While I have illustrated and described the preferred form of construction this is 90 capable of variation or modification without departing from the spirit of the invention. I therefore do not wish to be limited to the exact details of construction set forth but desire to avail myself of such variations and modifications as fairly fall within the scope of the appended claims.

I claim—

1. In a device of the class described, the combination with a window frame of socket 100 plates arranged to be secured to said frame and form vertical sockets therewith; shade roller supports secured to said socket plates; and curtain rod supports, each comprising a horizontal wire supporting member having 105 a downwardly turned U-shaped loop at its inner end adapted to be inserted in said socket, the said loop being formed in a vertical plane at an angle to said horizontal member, substantially as described.

2. In a device of the class described, the combination with a window frame of socket

plates arranged to be secured to said frame and form vertical sockets therewith; shade roller supports secured to said socket plates; and curtain rod supports, each comprising a pair of horizontal wire supporting members of different lengths connected together by a downwardly turned U-shaped loop adapted to be inserted in said socket, the said loop being formed in a vertical plane at an angle 10 to said horizontal member, substantially as described.

3. In a device of the class described, the combination with a window frame of socket plates arranged to be secured to said frame and form vertical sockets therewith; shade 15 roller supports secured to said socket plates; and curtain rod supports, each comprising a

pair of horizontal wire supporting members of different lengths and having upwardly turned outer ends and connected together 20 by a downwardly turned U-shaped flattened loop adapted to be inserted in said sockets, said horizontal members being inclined outwardly in a horizontal plane with reference to said loop, substantially as de- 25 scribed.

In testimony whereof I have signed my name to this specification in the presence of two subscribing witnesses.

REINHARD WENDT.
